UNITED STATES PATENT OFFICE.

ELUE O. FRITCH, OF WATERTOWN, MASSACHUSETTS, ASSIGNOR TO HOOD RUBBER COMPANY, OF WATERTOWN, MASSACHUSETTS, A CORPORATION OF MASSACHUSETTS.

DESIGN FOR A TIRE.

53,494.

Specification for Design. Patented July 8, 1919.

Application filed April 4, 1919. Serial No. 287,623. Term of patent 14 years.

To all whom it may concern:

Be it known that I, ELUE O. FRITCH, a citizen of the United States, residing at Watertown, Massachusetts, have invented a new, original, and ornamental Design for Tires, of which the following is a specification, reference being had to the accompanying drawing, forming a part hereof.

Figure 1 is a plan view, and
Fig. 2 a transverse section.

I claim:

The ornamental design for a tire, as shown.
ELUE O. FRITCH.
